Primary Examiner — Karen E Kearney(74) *Attorney, Agent, or Firm* — Fulwider Patton LLP(57) **CLAIM**

The ornamental design for an USB snap hook flash drive, as shown and described.

DESCRIPTION

FIG. 1 is a perspective view of a USB snap hook flash drive showing my design, and showing the USB snap hook flash drive in a usage state.

FIG. 2 is a front elevational view thereof.

FIG. 3 is a rear elevational side view thereof.

FIG. 4 is a right side elevational view thereof.

FIG. 5 is a left side elevational view thereof.

FIG. 6 is a top plan view thereof.

FIG. 7 is a bottom plan view thereof.

FIG. 8 is another perspective view of the design of FIG. 1, showing the USB snap hook flash drive in a non-usage state.

FIG. 9 is a right side elevational view of FIG. 8.

FIG. 10 is a left side elevational view of FIG. 8.

FIG. 11 is a front elevational view of FIG. 8.

FIG. 12 is a rear elevational side view of FIG. 8.

FIG. 13 is a top plan view of FIG. 8; and,

FIG. 14 is a bottom plan view of FIG. 8.

The broken line showing of the connector in the Figures is included for the purpose of illustrating portions of the USB snap hook flash drive, and forms no part of the claimed design.
